UNITED STATES PATENT OFFICE.

FRANK HORATIO CRAM, OF MORRISVILLE, VERMONT, ASSIGNOR TO
FRANCIS A. CUSHMAN, OF PLYMOUTH, NEW HAMPSHIRE.

PAPER-MAKING MACHINE.

SPECIFICATION forming part of Letters Patent No. 417,545, dated December 17, 1889.

Application filed May 7, 1889. Serial No. 309,921. (No model.)

To all whom it may concern:

Be it known that I, FRANK HORATIO CRAM, a citizen of the United States, residing at Morrisville, in the county of Lamoille and State of Vermont, have invented certain new and useful Improvements in Paper-Making Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

Paper-board used in certain lines of manufacture has to be as strong as it is possible to make it. When used for shoe-counters, it will break in the bending or when being pressed into shape unless made of strong stock—such as jute and manila; but these are expensive. It has been found that pulp mixed with hair will answer the purpose at less cost; but the trouble has been to get the making-cylinder to take up properly pulp mixed with hair, as it will mat, felt, ball up, or fall back into the vat, and what goes to the felt will not be properly mixed.

The object of my invention is to cause the pulp and hair to be taken up by the making-cylinder smoothly and without matting up or falling back into the vat, so that the pulp-sheet forms on the felt evenly and well mixed, the hair being out of sight practically.

My invention will be described below, and pointed out in the claims.

Figure 1 is a perspective view, partly in section. Fig. 2 is a perspective view of a modified roll to take the place of the upper fluted roll.

Like letters refer to like parts.

T represents an ordinary pulp-vat, and xx may be the pulp-line.

A is the making-cylinder. In order that the moisture may pass through freely, it has a jacket a, of brass wire-cloth of coarse mesh, and above this another jacket b, of brass wire-cloth of fine mesh; but this cylinder may be made in any of the well-known ways.

Above cylinder A is the felt F, and B is a couch-roll. This roll may be supported by arms ff; or any of the usual ways of arranging the felt may be resorted to.

HH are ordinary stirring-rolls, so placed

as to prevent the pulp from settling under 55 the making-cylinder.

In order to cause the pulp to form evenly and remain on said cylinder A, I employ a fluted or ribbed roll D. This roll should not run within several inches of the felt, and not 60 nearer to the working-face of the cylinder A than from one to one and a half inch, and should not dip below the pulp-line of the vat to any greater distance; but of course I do not limit myself to the exact distances here 65 given. The ribbed roll D when revolving mixes the hair with the pulp and at the same time throws the mixture upon the face of cylinder A as it rolls out of the pulp, and in such an even manner that the pulp will not 70 mat up or fall back into the vat, but will pass onto the top of cylinder A, where it forms on the felt perfectly.

In Fig. 2, D' is a modified form of roll D, in which the surface of the roll is simply 75 studded with truncated wire nails, or the equivalent, and it is found in certain cases to work even better than roll D.

The improvement described is very simple and economical, and accomplishes the purpose in view perfectly, thus rendering it feasible to work wood pulp mixed with hair, or the equivalent, which has always been difficult to do in such a manner that the resulting pulp-sheet should have a proper admixture of the two ingredients.

Having fully described my invention, what I claim, and desire to secure by Letters Patent, is—

1. The combination, with the vat and the 90 making-cylinder, of a roll having projections on its surface, substantially as described, said roll being partly above and partly below the pulp-line of the vat and located near said cylinder, as and for the purpose set 95 forth.

2. The combination, with the vat, of the making-cylinder, the fluted roll D, located partly above and partly below the pulp-line and near the cylinder, substantially as described, and the felt bearing on the upper face of said making-cylinder, as set forth.

In testimony whereof I affix my signature in presence of two witnesses.

FRANK HORATIO CRAM.
